UNITED STATES PATENT OFFICE.

GARRET TERPENNING, OF JERSEY CITY, NEW JERSEY.

SURFACE-CLEANING IMPLEMENT.

Application filed March 5, 1927. Serial No. 172,961.

This invention relates to devices for holding sponges, mop material and similar articles used in cleaning surfaces.

It frequently occurs that such surfaces are so far remote, or otherwise inaccessible, that a long handled implement must be employed and also that the cleaning element be disposed at an angle to the handle.

It is therefore one object of the present invention to provide a simple but effective implement composed of a pair of hinged jaws pivoted to a handle, the jaws being held in positive adjustment by a handle carried detent, no springs or loose parts being used.

It is a further feature to arrange the jaws in such manner as to be opened or closed on the material gripped between them by the foot, leaving the hands free to maneuver the handle in retaining or releasing the jaws as may be desired.

Another purpose is to produce an implement of an essentially practical character despite its simplicity, that is easy of operation and which can be manufactured at a moderate expense.

These and corresponding objects and aims are accomplished by the novel construction, combination and arrangement of parts hereinafter described and shown in the accompanying drawing, forming a material part of this disclosure, and in which:—

Figure 1 is a rear plan view of the device.

Figure 2 is a side elevational view of the same in an operative position.

Figure 3 is a partial sectional view looking on line 3—3 of Figure 1.

Figure 4 is a side elevational view of the device in an inoperative, open position.

In the drawing, the numeral 10 designates an elongated, cylindrical handle having a flattened lower end stem 11 pivoted on a rod 12 passing through a substantially triangular block or jaw 13, the jaw being provided with a slot 14 to enable freedom of movement of the handle, and a flexible rectangular lug 15 on its inner surface near the front edge.

Hinges 16 on the rear of the jaw 13, on both sides of the slot 14, connect with a similar mating jaw having a rounded rear edge 18 and a slot 19 in register with the slot 14, to permit movement of the handle 10.

Fixed on the outer face of the jaw 17 on both sides of the handle 10, is a pair of racks

20 engageable with a detent 21, secured on the handle, for a purpose which will later be seen.

In operation, the jaws 13—17 are opened and a sponge 22 or other cleaning device, is inserted partially therebetween.

The jaws are then closed and squeezed together under pressure of the operator's foot while the handle is moved towards a vertical position relative to the jaws so that the detent 21 will engage the teeth of the racks 20, positively clamping the article between the jaws.

It may be understood that it will now be possible to reach places to be cleaned, in an easy manner.

To remove the cleaning device, the jaws 13—17 are pressed together, while the detent 21 is disengaged from the rack teeth permitting the jaws to be opened.

From the foregoing, it will be seen that a cleaning implement has been disclosed that is entirely practical, very simple and which can be manufactured at a moderate cost.

As changes of construction could be made within the scope of the invention, it is intended that all matter contained in the foregoing description or shown in the accompanying drawings shall be interpreted as illustrative and not in a limiting sense.

Having thus described my invention, what I claim as new and desire to secure by Letters Patent, is:—

1. An implement of the class described comprising a handle, a jaw pivoted at the end of said handle, a second jaw hinged to the first jaw, a rack fixed on said second jaw, and a detent carried by said handle to engage the teeth of said rack.

2. An implement of the class described comprising a handle having a flattened stem, a pair of jaws having an opening through which said stem freely passes, a hinge connecting said jaws, a pivot in one of said jaws on which said stem is mounted, a ratchet rack fixed on the outer side of the other jaw, and a detent carried by said handle to engage the teeth of said rack.

3. An implement of the class described comprising a handle having a flattened stem, a pair of jaws having a slot extending in from their rear edges, said jaws being relatively upper and lower, a hinge connecting said jaws at their rear edges, a pivotal connection between said handle stem and the

- lower jaw, said stem passing freely through the slot in the upper jaw, racks on the upper jaw, and means for adjustably engaging the teeth of said racks carried by said handle.
- 5 4. An implement of the class described comprising a handle having a flattened stem, a pair of jaws having an opening through which said stem freely passes, a hinge connecting said jaws, a pivot in one of said
- 10 jaws on which said stem is mounted, a flexible pad carried on the inner side of the lower jaw, and means carried by said handle to forcibly retain said jaws when adjusted in closed position.
- 15 5. An implement of the class described

comprising a handle having a flattened stem, a pair of spaced flat jaws, hinges connecting said jaws at their rear edges, said jaws being slotted to receive the flattened stem, a pivot connecting said jaw within the slot 20 of the lower jaw, a ridged surface on the outer side of the upper jaw, and means carried by said handle to engage said ridged surface at various points whereby the jaws are held in operative position.

Signed at New York in the county of New York and State of New York this 4th day of March, A. D. 1927.

GARRET TERPENNING.
